Primary Examiner—Janice E. Seeger
Attorney, Agent, or Firm—Rudnick & Wolfe[57] **CLAIM**

The ornamental design for a picture display, are shown and described.

DESCRIPTION

FIG. 1 is a top front perspective view of a picture display showing my new design;

FIG. 2 is a front elevational view thereof;

FIG. 3 is a top plan view thereof;

FIG. 4 is a right side elevational view thereof; the left side being a mirror image of the right side;

FIG. 5 is a rear elevational view thereof; and,

FIG. 6 is a cross-sectional view of the picture display taken along the line 6—6 in FIG. 5.

The particular figure depicted by broken lines is for illustrative purposes only and forms no part of claimed invention; the broken lines depicting an outer frame are for environmental purposes only and form no part of claimed invention.
